CLAIM

The ornamental design for a portion of a glove, as shown and described.

DESCRIPTION

FIG. 1 is a perspective view of a portion of a glove showing my new design;

FIG. 2 is a top plan view of the portion of a glove shown in FIG. 1;

FIG. 3 is a side view of the portion of a glove shown in FIG. 1; and,

FIG. 4 is a front view of the portion of a glove shown in FIG. 1.

The uneven broken line immediately adjacent to the shaded area represents the bounds of the claimed design. All other uneven broken lines represent the remaining portion of the glove. The uneven broken line representations in FIGS. 1-4 are for illustrative purposes only and form no part of the claimed design.
